UNITED STATES PATENT OFFICE.

CHARLES E. VERHUNCE, OF CHICAGO, ILLINOIS, ASSIGNOR TO R. WILLIAMSON & CO.,
OF CHICAGO, ILLINOIS, A CORPORATION OF ILLINOIS.

DESIGN FOR A PORTABLE LAMP-STAND.

49,045.

Specification for Design.

Patented May 9, 1916.

Application filed March 22, 1916. Serial No. 85,998. Term of patent 3½ years.

To all whom it may concern:

Be it known that I, CHARLES E. VERHUNCE, a citizen of the United States, residing at Chicago, in the county of Cook and State of Illinois, have invented a new, original, and ornamental Design for a Portable Lamp-Stand, of which the following is a specification, reference being had to the accompanying drawing, forming part thereof.

The figure is a perspective view of a portable lamp stand showing my new design.

I claim:

The ornamental design for a portable lamp stand, as shown.

CHARLES E. VERHUNCE.
